UNITED STATES PATENT OFFICE.

THOMAS B. JEFFERY, OF KENOSHA, WISCONSIN.

CATALYTIC IGNITER FOR EXPLOSIVE-MOTORS.

SPECIFICATION forming part of Letters Patent No. 747,182, dated December 15, 1903.

Application filed March 11, 1901. Serial No. 50,626. (No model.)

To all whom it may concern:

Be it known that I, THOMAS B. JEFFERY, a citizen of the United States, residing at Kenosha, county of Kenosha, State of Wisconsin, have invented certain new and useful Improvements in Catalytic Igniters for Explosive-Motors, of which the following is a specification, reference being had to the accompanying drawings, forming a part thereof.

10 The purpose of this invention is to provide a novel means of causing ignition of the explosive gaseous mixture in an explosive-engine.

It consists in the employment of a catalytic agent located in the explosion-chamber of the motor adapted to cause chemical combination of the intermixed gases to occur when such intermixed gases come into the presence of such agent and an arrangement of passages 15 by which the gases are forced into the presence of such agent and into the explosion-chamber, whereby the gases are ignited and the agent rendered incandescent, causing explosion of the motive-power gases in said 20 chamber. The invention, however, is not limited to a structure in which the gaseous mixture whose explosive combination generates the power is the same as that exposed to the action of the catalytic agent to be brought 25 into combination by that agent and thereby to render the agent incandescent, nor is it limited strictly to the use of means for compressing the gases or introducing them under 30 compression into the presence of the catalytic agent; but the most economical and practical 35 form of the invention I consider to be one in which the same gaseous mixture whose explosion is to generate the motive power is used for the purpose of being exposed to the 40 action of the catalytic agent, and specifically in which such gases are taken from the piston-chamber of the motor after being partially 45 compressed in that chamber and are further compressed by additional means for the purpose of being again discharged back into the explosion-chamber and into contact with the catalytic agent.

The invention consists, further, in specific features of construction which are set out in 50 the claims.

In the drawings, Figure 1 is an axial section through the cylinder of an explosive-mo-

tor embodying my invention. Fig. 2 is a detail section at the line 2 2 on Fig. 1.

A is a cylinder of a gas-engine; A', the compression and explosion chamber at the end of the cylinder. B is the piston operating in the said cylinder or piston-chamber.

C is the main crank-shaft of the engine; C', the crank-arm thereon; C², the pitman-link connecting the crank with the piston.

D is a pump-cylinder collateral to and parallel with the motor-piston chamber or cylinder A.

E is a pump piston or plunger operating in the pump-cylinder D.

The pump-cylinder D is made integral with the cylinder A. Through the head of the cylinder A a bore is made transversely across the cylinder D, leading into the compression and explosion chamber A', and in this bore is inserted a plug G, provided at its outer end with a head G', by which it may be rotated, and immediately forward of the head with a threaded boss G¹⁰, by which it is screwed into the outer end of the bore in which it is inserted, as seen in Fig. 1. This lug is axially apertured to receive a tubular shell H, which is designed to protrude beyond the inner end of the plug slightly into the compression and explosion chamber A', while at the opposite end it forms a stop for a check-valve in the form of a ball J, which is retained at the opposite side by a tubular stop J', which is screwed into the outer end 85 of the plug G. The inner end of the stop J is formed as a seat for the valve G. A port d leads from the end of the pump-cylinder D through the plug G and shell H into the cavity of the shell, the communication thus 90 opened outward from the pump-cylinder through the axial cavity of the stop J being cut off by the check-valve J'. The shell H may be termed a "cartridge," its inner end being closed by fine-meshed platinum wire-gauze K, through which any gas or air forced from the pump-cylinder into the explosion-chamber A' must pass to be discharged within 95 said explosion-chamber. The platinum gauze from the well-known catalytic property of finely-subdivided platinum tends to cause combination of the intermixed gases in turn heats the platinum and increases

its tendency to cause such combination until finally it becomes incandescent and causes the gases to unite with an explosive flash or flame, which itself, independently of the incandescence of the platinum, explodes the motor-power gases in the explosion-chamber. In addition to the platinum gauze the cartridge-shell H may contain spongy platinum or "black platinum," whose catalytic property is more marked in some respects than the bright platinum gauze. k may represent the position of such spongy platinum or black platinum in the shell H; but I do not limit myself to using both the gauze and the spongy or black platinum, nor to using either in preference to the other. Since the gas to excite the catalytic agent is to be driven through it for that purpose, the catalytic agent is desirably located as shown, obstructing a passage through which a current of gas is driven. Since it is also desirable that said catalytic element should be directly exposed to the heat of the motor-gases in the explosion-chamber, it is extended, as shown, from the end of the shell, and the shell itself, as above stated, is protruded into the chamber to facilitate this purpose, so that a portion of the catalytic element is in the passage formed by the shell at a portion of such shell which is within the explosion-chamber, and a further portion of the catalytic element is formed, so that it constitutes to an extent a continuation of the passage, but is beyond any guarding-wall thereof and stands out within the explosion-chamber. Thus the same catalytic element performs two functions in conjunction with the means for directing the excitant-current through it—to wit, first, of becoming excited by the movement of such current; second, exposing itself in this excited condition to the gases which are to be ignited by it and being exposed to the heat of such explosion supplementing the heat developed by the movement of the excitant-gases through it. For convenience in thus preliminarily heating the platinum I make the cartridge H as shown, so that it may be readily withdrawn to heat the platinum by outside means, as in a lamp-flame or otherwise, whereupon it may be immediately reinserted and secured. To revive the temperature of the platinum after the engine has been at rest for a short time, a gaseous mixture adapted to excite and be acted upon by the platinum may be pumped into the cartridge by any suitable appliance attached to the outer end of the tubular stop J'. I have shown for that purpose a rubber bulb M with proper connections, which may be understood as leading from any source of suitable gas mixture. A duct a' is formed leading from the cylinder A at a distance back from the explosion-chamber A' into the pump-cylinder B for the purpose of admitting the gaseous mixture from the cylinder A into the pump-cylinder for the purpose of being forced therefrom through the cartridge K to excite the catalytic agent, as explained.

C¹⁰ is a gear-wheel on the shaft C. C²⁰ is a gear-wheel of double the size of the wheel C¹⁰, meshing with and driven by the latter, the shaft c² of the gear C²⁰ being in line with the pump-piston E and carrying a cam C³, of the form shown in Fig. 1, having the radial edge C³⁰ and the eccentric edge C³¹, the latter extending through only one hundred and eighty degrees of the circle about the axis of the shaft, the remainder of the periphery being concentric with the shaft, the entire periphery of the cam forming a track for an abutment in the form of a stud and roll E¹⁰ on the arm E' of the pump piston or plunger E. Said arm obtains guidance in the lug A³⁰, which projects from the side of the frame-plate A³ of the engine, and it has below the abutment E¹⁰ a stop-shoulder E¹¹, between which and the lug A³⁰ a spring L is coiled about said arm E', tending to resist the withdrawing movement of the plunger E from the cylinder D and to thrust the plunger back into the cylinder forcibly. The shaft c² revolves in the direction shown by the arrow in Fig. 1, causing the cam C³, operating against the abutment E¹¹, to forcibly withdraw the plunger E in the cylinder D until said abutment reaches the point c³⁰ at which it runs off the eccentric periphery of the cam and follows down the straight edge C³⁰ directly toward the shaft under the force of the spring L. The cam is so situated on its shaft with respect to the position of the crank C' on the shaft C as to cause the inthrust of the plunger E under the force of the spring L to occur in each alternate revolution of the crank-shaft at the point at which the piston E has nearly completed its inward compressing movement. It will be noticed, therefore, that a little before this inthrust of the plunger occurs the piston E will have been at a position at which the duct a' has been uncovered, opening free communication between the engine-cylinder and the pump-cylinder, while both pistons are withdrawn back from the point of communication, thus admitting from the motor-cylinder into the pump-cylinder the gas which has been compressed to such extent as the movement of the piston D up to the opening of the duct a' may have caused. The quick inthrust of the plunger E into the pump-cylinder under the action of the spring L will cause the partly-compressed gases which are in the pump-cylinder to be still further compressed, so that they will be discharged through the port d into the cavity of the shell H and through the finely-subdivided or black platinum therein into the explosion-chamber A'. This forcible introduction of the compressed gases into the presence of the spongy or finely-subdivided platinum will cause the chemical union of the mixed gases, producing explosion and flame at that point and heating the platinum to incandescence, so that both by the incandescent platinum and by the jet of flame which will emerge from the end of the cartridge-shell H into the ex-

losion-chamber the gases in that chamber, now fully compressed by the compressing stroke of the piston B, will be ignited and the explosion produced which will thrust back the

5 piston. The precise point in the compressing stroke of the engine-piston at which the explosion is caused to occur may be varied as conditions require by angularly adjusting the cam C³ on the shaft c². This may be done by 10 the tangent-screw c⁴, mounted on the cam and engaging the segment-rack c⁵ on the shaft.

I claim—

1. In an explosive-motor, a catalytic agent located in the explosion-chamber and exposed 15 to the motive-power gases to be exploded therein; a source of gaseous mixture adapted to be caused to form a chemical combination by the presence of such agent; and means operated in controlled time relation with the motor for forcing said gaseous mixture into contact with said agent, whereby the latter is rendered incandescent at the explosion stage in 20 the cycle of the motor's action.

2. In an explosive-motor, an igniting means 25 comprising a source of inflammable gaseous mixture; a passage leading from such source and discharging in the explosion-chamber of the motor; means for driving the inflammable gaseous mixture through such passage into 30 the explosion-chamber, and a catalytic agent exposed in the path of the current thus produced in such passage.

3. In an explosive-motor, an igniting means comprising a source of inflammable gaseous 35 mixture; a passage from such source and discharging in the explosion-chamber of the motor; a catalytic agent located in the path of a current through such passage, adapted to cause the gaseous mixture to become inflamed 40 in its presence; and means operated in controlled time relation to the motor's action for driving the gaseous mixture through the passage toward the explosion-chamber, whereby such gaseous mixture may be discharged as 45 flame into the explosion-chamber at the explosion stage in the cycle of the motor's action.

4. In an explosive-motor, an igniting means comprising a catalytic agent; a source of gaseous mixture adapted to be caused to form a 50 chemical combination by the presence of such agent; means operated by the motor, for compressing such mixture in the presence of the catalytic agent to a degree in excess of the compression of the motor-gases produced by 55 the compression-stroke of the motor, and for driving such gaseous mixture thus compressed past the catalytic agent and discharging it in the explosion-chamber.

5. In an explosive-motor, an igniting means 60 comprising a catalytic agent; a source of gaseous mixture adapted to be caused to form a chemical combination by the presence of such agent; means operated by the motor for compressing such mixture to a degree in excess 65 of the compression produced in the motor-gases by the compression-stroke of the motor-piston, and for driving such mixture so com-

pressed through the catalytic agent during a short portion of the piston's compressing stroke toward the culmination of such stroke, 70 and discharging it, after passing such agent, within the explosion-chamber.

6. In an explosive-motor, a catalytic agent located in the explosion-chamber and exposed to the motor-gases; a source of gaseous mixture adapted to excite the catalytic agent; means operated in controlled time relation with the motor for compressing such excitant-gases and driving them so compressed through the catalytic agent during the concluding 80 portion of the piston's compression-stroke.

7. In an explosive-motor, an igniting means comprising a source of inflammable gaseous mixture; a passage leading from such source and discharging in the explosion-chamber of 85 the motor; a catalytic agent, adapted to be excited by such mixture, and means operated by the motor for compressing such mixture to a degree in excess of the compression of the motor-gases produced by the motor-piston, and driving the same thus compressed through the passage past the catalytic agent, and causing it to be discharged in the explosion-chamber, said compressing and driving means being timed to operate for compression and discharge of the mixture during the concluding portion of the piston's compressing 95 stroke.

8. In an explosive-motor, a catalytic agent located in position to be exposed to the motor-gases in the explosion-chamber; a source of gaseous mixture adapted to excite such catalytic agent; means operated by the motor for compressing such excitant-gases to a degree in excess of the compression of the 105 motor-gases produced in the piston-chamber; the mechanism for affecting such compression, being timed to commence the compressing action toward the end of the piston's compressing stroke; whereby the excitation 110 of the catalytic element by said excitant-gases occurs toward the finish of said compressing stroke.

9. In an explosive-motor, an igniting means comprising a source of inflammable gaseous 115 mixture; a passage leading from such source and discharging in the explosion-chamber of such motor; a catalytic agent adapted to be excited by such mixture and means operated by the motor for discharging such mixture through the catalytic agent inside of explosion-chamber at the stage of compression of the motor-gas in said chamber.

10. In an explosive-motor, a catalytic agent located in a position to be exposed to the motor-gases in the explosion-chamber; a source of gaseous mixture calculated to excite such catalytic agent; means provided for discharging such excitant mixture through the catalytic agent at the compression stage of 125 the motor-gas into the explosion-chamber.

11. In an explosive-motor, an igniting means comprising a collateral piston-chamber having communication with the explo-

sion-chamber; a piston in such chamber, and means whereby the same is reciprocated in controlled time relation to the movements of the motor-piston; and a catalytic agent located in the path of a current through the communicating passage from the said collateral piston-chamber to the explosion-chamber of the motor adapted to cause a chemical combination between the elements of the explosive employed, and means for admitting such explosive to the collateral piston-chamber in advance of the piston, whereby such explosive is forced into the presence of the catalytic agent and discharged as flame in the explosion-chamber.

12. In an explosive-motor, in combination with the piston-chamber of the motor, a collateral piston-chamber having communication with the motor-piston chamber at a distance back from the explosion-chamber, and a passage communicating between said collateral chamber and the explosion-chamber; a catalytic agent located in the path of a current through said passage, and means for operating the piston in said collateral chamber in controlled time relation to the motor-piston to cause the gaseous mixture supplied to the motor for explosion to be drawn from the motor-piston chamber into the collateral chamber, and to be compressed in the latter and discharged therefrom into the explosion-chamber past the catalytic agent, whereby said gases may be ignited and discharged as flame in the explosion-chamber.

13. In an explosive-motor, an igniting means comprising a pump device having an intake leading from the motor-piston chamber, and a discharge leading into the explosion-chamber; a catalytic agent located in the path of a current through the discharge-passage; and means for operating such pump in controlled time relation to cause it to draw gases from the motor-piston chamber during the compressing movement of the motor-piston, and to discharge the same past the catalytic agent into the explosion-chamber.

14. In an explosive-motor, an igniting means comprising a pump device having an intake leading from the piston-chamber of the motor, and a discharge leading into the explosion-chamber, a catalytic agent located in the path of a current through the discharge-passage, and means for operating such pump in controlled time relation to the motor-piston to cause it to draw explosion-gases from the motor-piston chamber, and to compress the same and discharge them under compression past the catalytic agent into the explosion-chamber at the explosion stage of the cycle of the motor's action.

15. In an explosive-motor, in combination with the piston-chamber of the motor and the piston therein, the explosion-chamber at the limit of the piston's stroke; a pump-chamber collateral to the motor-piston chamber, and a discharge-passage therefrom into the explosion-chamber; a catalytic agent located in

the path of a current through such discharge-passage; a source of supply for gases adapted to be acted upon by such catalytic agent, and a passage by which the same are admitted to the pump-chamber in advance of the piston; a cam operated in controlled time relation to the main shaft of the motor, and connections by which such cam withdraws the piston in the pump-chamber; and a spring tending to thrust said piston forward in its chamber; the cam being provided with an abrupt drop to permit the spring to operate on the piston to give it a quick inthrust, whereby the gases are forcibly discharged from the pump-chamber past the catalytic agent into the explosion-chamber.

16. In an explosive-motor, in combination with the piston-chamber and the explosion-chamber at the limit thereof, a pumping device having a discharge-passage from its chamber into the explosion-chamber; a catalytic agent located in the path of a current through such discharge-passage; a source of supply for a gaseous mixture, adapted to be acted upon by such catalytic agent; the piston of such pumping device, and a spring adapted to thrust it forward to cause discharge into the explosion-chamber; and devices operated in controlled time relation with the main shaft of the motor for withdrawing the piston, arranged to release it to permit the spring to act abruptly, whereby the gases admitted to the pump-chamber are forcibly discharged past the catalytic agent into the explosion-chamber.

17. In an explosive-motor, in combination with the explosion-chamber, a pump device having a discharge-passage leading into such chamber; a source of supply for a gaseous mixture, adapted to be acted upon by a catalytic agent; and a holder for such catalytic agent in the discharge-passage, arranged to be withdrawn and reinserted at will.

18. An explosive-motor, comprising, in combination with the explosion-chamber, a pump device discharging thereinto, and a catalytic agent located in the path of a current through the discharge-passage; a source of gaseous mixture adapted to be acted upon by such catalytic agent; the pump device having its intake connected to such source; a duct leading from the discharge-passage outwardly; and means for closing the same.

19. An explosive-motor, comprising, in combination with the explosion-chamber, a pump device discharging thereinto, and a catalytic agent located in the path of a current through such discharge-passage; a source of gaseous mixture adapted to be acted upon by such catalytic agent; the pump device having its intake connected to such source; a duct leading from the discharge-passage outwardly; and a check-valve in such discharge-passage seating outwardly to close the same against outward discharge.

20. In an explosive-motor, a catalytic agent; a source of gaseous excitant for the same; a

passage containing such excitant, leading from such source to the explosion-chamber of the motor; means operated by the motor to force such excitant through the passage into the explosion-chamber; and means for varying at will the time in the cycle of the motor's action at which said forcing means operates.

21. In an explosive-motor, a source of gaseous excitant for a catalytic agent; a passage leading from such source to the explosion-chamber of the motor; a catalytic agent located in the path of gaseous current through such passage; a pump-chamber constituting part of such passage; a shaft rotating in uniform time relation to the motor main shaft; a cam thereon and a pump-piston connected to and operated by such cam, and means for angularly adjusting the cam on its shaft at will.

22. In an explosive-motor, a source of gaseous excitant for a catalytic agent; a passage

leading from such source to the explosion-chamber of the motor; a catalytic agent located in the path of gaseous current through such passage, means for impelling such gases 25ous excitant through such passages comprising a shaft rotating in uniform time relation to the motor main shaft; a cam thereon and a pump having its piston connected to and operated by such cam; a tangent-screw mounted on the cam, and a segment-rack mounted on the shaft and engaged by the tangent-screw, whereby the cam may be angularly adjusted on the shaft.

In testimony whereof I have hereunto set my hand, at Kenosha, Wisconsin, in the presence of two witnesses, this 1st day of March, A. D. 1901.

THOS. B. JEFFERY.
